UNITED STATES PATENT OFFICE.

ALLAN O. CARPENTER, OF CORNING, NEW YORK, ASSIGNOR TO INGERSOLL-RAND COMPANY, OF JERSEY CITY, NEW JERSEY, A CORPORATION OF NEW JERSEY.

OILING DEVICE.

Application filed July 20, 1925. Serial No. 44,717.

To all whom it may concern:

Be it known that I, ALLAN O. CARPENTER, a citizen of the United States, and a resident of Corning, in the county of Steuben and 5 State of New York, have invented a certain Oiling Device, of which the following is a specification accompanied by drawings.

This invention relates to oiling devices for compressors, pumps, and the like, but 10 more particularly to an oiling device for duplex machines by means of which oil or other lubricant is efficiently supplied to each crank for splash lubrication.

The objects of the invention are to produce 15 a simple and efficient oiling device operated by an oil elevator of any suitable character which could be any form of pump and will supply the lubricant separately to the splash troughs from which the oil will 20 be returned through an overflow chamber into the oil reservoir and elevator chamber at a lower level so that the oil may be used over again.

Further objects of the invention are to enable 25 the compressor to stand at an angle laterally and yet maintain sufficient oiling, and produce an oiling system operative for either direction of crank shaft rotation.

Another object of the invention is to enable 30 the entire oiling device to be inclosed within the crank case.

The invention is shown in one of its preferred forms in the accompanying drawings, in which—

35 Figure 1 is a diagrammatic sectional elevation of a duplex compressor having the oiling device applied thereto.

Figure 2 is a detail vertical sectional view taken through the sump chamber containing 40 the oil elevating gears.

Figure 3 is a horizontal sectional plan view taken through the oiling device on the line 3—3 of Figure 1 looking in the direction of the arrows, and

45 Figure 4 is a view through Figure 3 on the line 4—4 looking in the direction of the arrows.

Referring to the drawings, the cylinders A and B of the compressor are provided 50 with the usual reciprocating pistons C and D driven from the crank shaft E having the cranks F and G which are provided with the usual splashes H and J. The compressor is provided with the usual valves and intake and discharge connections and may be

driven from any source of power, but these details form no part of the present invention and need not be further described.

The crank case K is in this instance divided at its lower portion into two main compartments L and O having different levels, the compartment L being at a lower level than the compartment O, and the higher compartment O is again divided into splash troughs P and Q and an overflow chamber R. The splashes H and J are adapted to dip into the lubricant in the splash troughs P and Q in the usual manner.

The lower compartment L is also subdivided into a sump chamber S in which two gears acting as an oil elevator are located, comprising the gears T and U conveniently driven from the crank shaft E. The other chambers of the lower compartment L comprise the oil receiving pockets V and W and the return flow chamber X, which return flow chamber communicates with the overflow chamber R by means of the passage Y and also communicates with the chamber S through the passage Z.

The conduits or pipes a and b connect the oil receiving pockets V and W with the splash troughs P and Q respectively at a level above the bottom of said chambers, so that oil elevated into the oil pockets flows 85 to the splash troughs, and may overflow from them over the partitions c and d into the overflow chamber R and from thence through the passage Y into the return flow chamber X at a lower level and back into the chamber S. These partitions c and d and c' and d' are lower at the center than at the ends, so that an approximately constant oil level may be maintained when the compressor is inclined laterally.

The oiling device is simple, operates efficiently and keeps both of the crank chambers filled with oil as required. Obviously the invention is not limited to any particular type of oil elevating device nor is it limited to the precise details of construction and arrangement shown in the drawings, as those skilled in the art will be enabled to devise equivalent constructions without departing from the spirit of the invention as defined 105 in the appended claims.

I claim:

1. An oiling device for duplex compressors, pumps and the like comprising in combination, a crank shaft, and cranks, a 110

- 2
- crank case, splash troughs, and an over-flow chamber, a sump chamber at a lower level containing oil elevating gears, oil receiving pockets, conduits leading from the oil receiving pockets through the walls of and into the splash troughs respectively, and a return flow chamber at a lower level than the overflow chamber and communicating therewith and with the sump chamber.
  - 10 2. An oiling device for duplex compressors, pumps and the like, comprising in combination a crank shaft and cranks, a crank case divided at its lower compartment into two compartments having different levels, 15 the higher compartment being again divided

into an overflow chamber and troughs into which the splash oilers of the cranks dip, the lower compartment being also subdivided into a sump chamber containing oil elevating gears, oil receiving pockets, and a return flow chamber communicating with the said overflow chamber of the higher compartment, and pipes leading from the said oil receiving pockets through the walls of the said splash troughs for delivering oil to the said splash troughs. 20 25

In testimony whereof I have signed this specification.

ALLAN O. CARPENTER.
